UNITED STATES PATENT OFFICE.

ROBERT Z. DRAKE, OF OMAHA, NEBRASKA.

BRIDGE-REENFORCING MEANS.

Application filed January 19, 1923. Serial No. 613,567.

To all whom it may concern:

Be it known that I, ROBERT Z. DRAKE, a citizen of the United States, residing at Omaha, in the county of Douglas and State 5 of Nebraska, have invented certain new and useful Improvements in Bridge-Reenforcing Means, of which the following is a specification.

This invention has for its objects to provide means for reenforcing truss span bridges, and to correct defects in their alignment, and includes, for a single bridge, two girders adapted to be supported at their ends upon the same ground supports, such as 15 bents, piers or abutments, which support the truss span, for use in sustaining vertically applied stresses or loads independently of truss span, but adapted when depressed by a certain amount of weight or load, to be supported by the truss span bridge, so that the latter will co-operate with the girders in sustaining an excessive or required load, said girders and posts of the truss span being provided with attachments by means of 25 which the truss span may be adjusted and placed in perfect alignment.

In many instances it occurs that truss bridges which may have been in use for a considerable time are found to be inadequate for sustaining the weights of loads incident to their present uses, the reason for this being that motor-driven trucks and tractors, together with trailers, are now in general use, these often being heavily loaded, and the weight and stresses being much greater than formerly, the result being that these old bridges must be reinforced or replaced by new ones which will be adequate to sustain the required 40 stresses or weight, a new bridge, of course, being a considerable expense.

By use of the reenforcing means and alignment feature now presented, the piers and truss span of an old bridge may be 45 utilized, said reenforcing means being of such construction and arrangement that it will co-operate with the old structure for sustaining the required weight, and at, comparatively, a moderate cost, the alignment attachment operating to dispose for and maintain the reinforced bridge in symmetrical form and increasing the value of the truss.

With the foregoing objects in view the 55 invention presents a novel and useful con-

struction, combination and arrangement of parts, as described herein and claimed, and as illustrated in the accompanying drawing, wherein,—

Fig. 1 is a view showing a part of the reinforced bridge in longitudinal section, and the remaining figures are enlarged detail views relating to Fig. 1. Fig. 2 shows an end portion of the reinforced bridge in longitudinal section. Fig. 3 shows a side view 65 of a locking-plate of the aligning attachment, mounted on a reinforcing girder. Fig. 4 is a broken away view in transverse section, showing one of the aligning attachments which connects a reinforcing 70 girder with a post of a truss span. Fig. 5 is a side view of the parts shown in Fig. 4. Fig. 6 is a plan view of a locking-plate and part of a girder. Fig. 7 shows the ends of 75 a girder and truss span mounted on a ground support.

Referring now to the drawing for a more particular description, the invention is shown and described in connection with the truss 6 and ground-supports or piers 80 7 of an old bridge, said parts being utilized in connection with the reinforcement and aligning means now provided.

In the practice of the invention, the joists and floor of an old truss bridge are removed, 85 one of the objects being to reduce the weight of the old bridge since the joists and floor formerly used will not be needed; then alignment box-frames 8 are provided for connecting the posts 9 of the old bridge 90 span with the cross-beams 10, said frames furnishing a suitable mounting for the adjusting or aligning-bolts 11. However, any mounting may be provided for the bolts 11 which will support them stationary, above 95 and approximately parallel with the beams 10 in such a manner that the frames 8 may be adjusted to a vertical position.

The frames 8 may be of any suitable construction which will provide means for rigidly connecting the posts 9 with the beams 10, and will have such strength that the weight, when applied to said beams will be sustained by the truss span 6, and will provide a mounting for the bolts 12 upon which the stay-rods 13 for the truss span are mounted, and will also provide a stationary mounting for the horizontal aligning-bolts, as mentioned. In the present instance I have shown the box frame 8 to consist of a pair 105 110

of side plates *a* which provides a mounting for the bolts 11 and 12, said plates having flanges *b* and being connected and reinforced by means of brace-blocks *c*, the upper ends 5 of the frames 8 being secured to the posts 9, and the lower ends of said frames being seated on the beams 10 and secured thereto by the inverted U-bolts *d* which engage the bolts 12.

10 It will be understood that if the end-braces 14 for the truss span are suitably secured to the ground supports or piers at the respective ends of a bridge, the function for the truss span in supporting a weight may 15 be fully discharged, said weight being applied to the beams 10, and the invention includes means which co-operate with the truss span whereby a greater weight may be supported than formerly.

20 This is accomplished by the use of a pair of girders 15 and parts mounted thereon, said girders being disposed adjacent to the inner sides of the box frames 8 and supported at their ends by the piers or ground- 25 supports 7, spacing-plates 16 preferably being used at the ends of the I-beams or girders 15 and disposed between said girders and the caps 17 of the piers, the thickness of said plates 16 being such that spaces *x* will normally 30 be maintained between the lower flanges of the girders 15 and the upper flanges of the beams 10.

Numerals 18 indicate floor-joists which are disposed transversely of the girders 15 35 and are supported at their ends upon the strips of angle iron 19 which are secured to the girders, said floor joists also being secured to the girders by means of angle plates 20, and operating to support the planks 21 40 for a floor 22, the planks being disposed parallel with the girders with their upper sides preferably disposed in line with the uppermost parts of the girders, this arrangement for placing the floor plank parallel with the girders and parallel with the line of vehicle travel being a decided advantage since the planks will present a more even surface for the vehicle wheels, and when thus disposed a lesser number of 45 planks, obviously, will be exposed to wear. It will also be seen that the placing of the floor joists 18 transversely of the girders 15 and securing them rigidly to said girders at short intervals, adds immeasurably to the 50 carrying value of the girders by preventing side deflection and torsion usually found in long girders under load. The present construction permits the girders to move downward readily when loaded beyond their 55 fixed capacity.

It will thus be seen that the girders 15 which support the floor 22 may support a load of certain weight without any stresses being directed to the old truss span. However, in operation, the load on the floor 22

may be so great that the girders, between their ends, may be bent downwardly or deflected until the lower flanges of said girders are pressed upon the beams 10, so that said beams, together with the truss span 6 70 will sustain stresses, and by the construction described, the old and new parts co-operate to great advantage; and by use of the invention, old bridges may be so reinforced that they may sustain any required weight, 75 at comparatively, a limited cost.

Any suitable means may be provided for maintaining the posts 9 and box frames 8 in vertical alignment and in uniformly spaced relation with the girders 15 and parallel with the webs of said girders, said means, of course, permitting a depression of the girders, the means shown herein consisting of the threaded, stationary aligning bolts 11, each being adjustably mounted in the side plates *a* by means of suitable keepers *e* and each being provided with a head *f* engaging in a vertical channel *g* formed in a locking-plate or block 23, each block 23 being secured to a girder 15 and being provided with a vertical slot *h* opening on a channel *g* for receiving a reduced part or neck *k* of a bolt 11, these parts being of such proportions that expansion or contraction of the girders or other metallic parts will not prevent or interfere with operation; and it will be understood that the girders may move freely to a depressed position into engagement with the beams 10 when sustaining a certain weight, or may move to their normal position, the bolts 11 remaining stationary with their heads loosely engaging in the channels *g*, the result being that the posts 9 will be maintained in a vertical position, equidistant from the girders, whether the girders are depressed or at normal position.

It will be understood that, as described, the bolts 11 operate as coupling members, and since the webs of the girders will remain in a vertical position, the keepers *e* may be rotated for adjusting the position of the box frames 8 to cause said frames and posts 9 to move to a vertical position and to be thus maintained.

Since the joists are disposed at short intervals transversely of the girders and secured thereto, as described, these parts operate as a unit and form a rigid base, the width of which is equal to the width of the roadway of the old truss span, and the rigid construction mentioned, in connection with the bolts 11 and their operation, adds greatly to its value for use in aligning the members of the old truss span.

While, in the drawing, piers have been shown for supporting the old truss span and reinforcing girders, it will of course be understood that the invention is operative in instances where other ground supports are

employed, and in the claims, the piers, bents or abutments, for convenience, are designated as ground-supports.

While I have specifically shown and described construction, it will be understood that changes may be made in size, form, proportion of parts and minor details, said changes being determined by the scope of the invention as claimed.

10 I claim as my invention,—

1. The combination with the truss span of a bridge, said truss span being provided with cross-beams and having its ends disposed on ground supports, of girders mounted to 15 permit movements independently of the truss span and provided with a floor, said girders being normally disposed above and adjacent to the cross-beams and engaging said ground supports and adapted to be 20 deflected downwardly into engagement with said cross-beams.

2. The combination with the ground supports and truss span of a bridge, said truss span being provided with posts arranged in 25 pairs at its opposed sides and having cross-beams extending between and connected with the posts of each pair, of girders connected with and adapted to have vertical movements independently of the truss span and 30 provided with a floor, said girders being disposed above and normally disengaged from the cross-beams with their ends on said ground supports and adapted to be deflected between their ends for engaging 35 said cross-beams.

3. The combination with the truss span of a bridge, said truss span being mounted on ground supports and having cross-beams adapted to support an applied 40 weight, of a pair of girders connected with and adapted to have movements independently of said truss span, joists disposed transversely of and secured to the girders, planks parallel with the girders and secured to said joists, said girders being mounted on the ground supports and adapted to support an applied weight while disposed above and adjacent to the cross-beams and adapted to be pressed downwardly upon the cross-beams when an additional weight is applied thereto to permit the cross-beams to support said additional weight.

4. The combination with the ground supports and truss span of a bridge, said truss span including posts arranged in pairs at its opposed sides, of a plurality of frames each extending below and secured to a post, cross-beams having their ends secured to 50 the frames of the posts of each pair, girders provided with a floor, said girders being disposed above and normally disengaged from the cross-beams with their ends engaging said ground supports, and a plu-

rality of bolts for coupling the frames with 65 the girders and for maintaining them in spaced relation and permitting the girders to be pressed downwardly into engagement with the cross-beams.

5. The combination with the ground supports and truss span of a bridge, said truss span being provided at its sides with posts arranged in pairs opposite to each other and having cross-beams connecting the 70 posts of each pair, of a plurality of girders, joists disposed transversely of and secured to the girders, planks secured to the joists and disposed parallel with the girders, said girders being disposed above in 75 normal disengagement with the cross-beams with their ends upon said ground supports, and a plurality of aligning-bolts connecting the posts with the girders for maintaining them in spaced relation and permitting the girders to engage the cross-beams when said girders are pressed downwardly.

6. In reenforcing means for a bridge, the combination with a truss span having its ends mounted on ground supports, said 90 truss span including posts and being provided with cross-beams which extend between and are secured to the lower ends of the posts, of a pair of girders above and normally disengaged from the cross-beams 95 and mounted at their ends upon said ground supports, floor joists disposed transversely of and secured to the girders, planks on the floor joists having their upper sides disposed approximately in line 100 with the uppermost parts of the girders, and elements connecting the posts with the girders for maintaining them in spaced relation and permitting the girders to engage the cross-beams when deflected by a 105 sufficient weight applied thereto.

7. The combination with the truss span of a bridge, said truss span having its ends mounted on ground supports and provided with cross-beams adapted to resist stresses, of a pair of girders loosely connected with and adapted to have vertical movements independently of the truss span and provided with a floor and mounted at their ends upon said ground supports, said girders 110 being adapted to resist stresses directed thereto by a weight while disposed above and disengaged from the cross-beams and adapted to move into engagement with the cross-beams when additional stresses are 115 directed thereto to permit said additional stresses to be resisted by said truss span.

In testimony whereof, I have affixed my signature in presence of two witnesses.

ROBERT Z. DRAKE.
